Jas. Brown.

United States Patent Office.

HENRY J. RUGGLES, OF POULTNEY, VERMONT.

Letters Patent No. 77,407, dated April 28, 1868.

IMPROVEMENT IN MOWING-MACHINES.

The Schedule referred to in these Letters Patent and making part of the same.

TO ALL WHOM IT MAY CONCERN:

Be it known that I, HENRY J. RUGGLES, of Poultney, in the county of Rutland, and State of Vermont, have invented an Improved Mowing-Machine; and I do hereby declare that the following is a full and exact description thereof, reference being had to the accompanying drawings, making part of this specification—

Figure 1 being a top view of the machine.

Figure 2, a side elevation thereof.

Figure 3, a view of the under side of a portion of the tongue or pole of the machine, with the draught-hook and chains connected therewith.

Figure 4, a view of the under side of a portion of the finger-bar and fingers.

Like letters designate corresponding parts in all of the figures.

The main frame E of the machine is suspended, near its centre, on the axle D, and revolves, or rises and falls, freely upon or around it. Back of the axle, in this main frame, are arranged the usual bevelled wheel and pinions, B c and b b, driven by the cog-wheels a a, on the driving-wheels A A. The crank e, on the driving-shaft C, drives the pitman d, for giving motion to the cutter-bar I.

On the downwardly-projecting corner Q of the main frame, opposite to the pitman-crank, is secured a strong plate, R, being bolted to the frame, so as to be adjustable in position, in order to allow the raising and lowering of the points of the knife-blades or cutters, to regulate the cut thereof. To this plate R is hinged the shoe S. The sliding end of the pitman d, connecting with the cutter-bar I, works over this shoe, and rises and falls with it, as the said shoe swings up and down with the frame E, and hence cannot get out of line with the cutter-bar. The driving-wheels A A, as they operate the gearing located on the rear end of the swinging frame E, produce an upward pressure on the said end of the frame, and consequently throw additional pressure upon the shoe D.

On both sides of the main frame E, near the front end thereof, are arranged, at different points, rings or eyes, t t t, from which extend upward, inward, and forward, two chains, s s, to a sliding hook, L, under the tongue H. This sliding hook moves in a guide or guides, m, and the extent of its movement is limited by a slot, p, therein, (or its equivalent,) embracing a pin in the guide. To this sliding hook the double-tree of the team is attached, and by this connection of the draught with the main frame E, which sustains the shoe S and cutter-bar I, the pressure of the same upon the ground, when the machine is at work, is graduated and controlled, the lifting or raising thereof being proportional to the resistance or weight of the grass in cutting; and, what is of great importance, the side-draught is adjusted and properly balanced by adjusting the two chains s s to the proper rings or eyes t t, on the sides of the frame, so as to draw more or less on one side than on the other. The black and red lines in fig. 3 indicate different positions of the draught L and chains s s, according to the resistance of the machine under different circumstances. All the resistance of the machine is thrown upon the traces of the team, and both light and heavy grass are managed with equal ease and certainty.

The finger-bar O is corrugated near the back edge, as indicated by the shade lines in fig. 1. This extends nearly the entire length of the bar, leaving only a few inches of the length, at each end, plain, for fastening the heel and toe shoes. This corrugation increases the stiffness and strength of the finger-bar, without increasing the material and weight thereof.

The knives or blades u u are secured to the under side of the cutter-bar I, as indicated, and thereby move with less friction and resistance.

The fingers w w are locked together on the under side of the finger-bar, as seen clearly in fig. 4. They are made with cutting-edges, bevelled backs, and are so shaped, in relation to the cutting-blades, that the shearing angle, between the cutting-edges of the fingers and blades, shall be the same at all points of contact, thus securing great ease and uniformity, as well as efficiency of cutting-action.

The journal-boxes of the whole machine are made "solid," or each in a single piece, as represented, so that there are neither caps nor bolts to get loose, thereby obviating loose joints.

There is a suspending-hook, T, pivoted to the tongue H, or its hounds G, for suspending the main frame E, to hold the working parts up from the ground, while transporting the machine, or when it is not in action.

The cutter-bar is raised by hand, at any time, by means of a lever, f, grooved eccentric g, secured to the lever, and a lifting-chain, j, substantially as represented.

The whole machine, constructed and operating as above described, is simple, every part of it is constantly in sight of the driver, is firm and durable, and the usual defects of mowing-machines are in it avoided.

What I claim as my invention, and desire to secure by Letters Patent, is—

The combination and arrangement of the swinging frame E, adjusting-rings t t t, or their equivalents, on the sides of the frame, the draught-chains s s and sliding draught-hook L, substantially as and for the purposes herein specified.

I also claim the suspending-hook T, arranged and operating substantially as herein specified.

The above specification of my improved mowing-machine signed by me, this 21st day of March, 1867.

HENRY J. RUGGLES.
